UNITED STATES PATENT OFFICE.

AUGUST PREUSSLER, OF KLETTENDORF, NEAR BRESLAU, GERMANY.

TILTING CAR.

1,081,061.

Specification of Letters Patent.

Patented Dec. 9, 1913.

Application filed October 25, 1912. Serial No. 727,674.

To all whom it may concern:

Be it known that I, AUGUST PREUSSLER, a subject of the German Emperor, and resident of Klettendorf, near Breslau, Germany, have invented certain new and useful Improvements in Tilting Cars, of which the following is a specification.

This invention relates to an improved tilting-car, the tilting receptacle of which 10 is mounted on rollers and adapted to be laterally shifted by means of a toothed gearing on its bottom and at the same time tilted.

The essence of the invention consists in 15 that the side walls, without being connected with the end walls, are with their lower edges pivoted to the bottom plate in an easily disengageable way and by arms, which engage the ends of their upper edges, are 20 movably coupled with auxiliary end walls which are rigidly fixed to the car frame, so that, upon the bottom connection being disengaged on the tilting side, the corresponding side wall opens when tilting, while the 25 other, swinging on its upper pivots, forms then an inclined plane which secures the receptacle in its tilted position. Thus, an easy tilting is obtained thereby while the danger of turning the car over is avoided.

30 The accompanying drawing shows the improved tilting-car.

Figure 1 is a side view of the car, and Fig. 2 a section on Fig. 1.

a^1 is the bottom plate of the tilting receptacle a which rests on rollers c of the car frame d said bottom plate being strengthened by beams a^2 and provided with toothed segments b . With the latter gear toothed wheels e , which are keyed on an axle f located in the longitudinal axis of the car

frame, so that by turning the crank g the receptacle can be put in tilting position. The end walls a^3 of the receptacle are rigidly fixed to the bottom plate, while the lateral walls a^4 , without being connected with the end walls, are connected in any easily disengageable way with the bottom plate by the engagement of bolt i with lugs h (Fig. 1) and at the ends of their upper edges movably connected by arms k with a pair of auxiliary end walls d^1 fixed on the car frame d . Upon the bottom connection h , i of the side wall facing the tilting side being disengaged by reversing the bolt lever z^1 and the receptacle being tilted, the tilting side 55 opens, while the other side wall is, by the bottom, caused to form an inclined plane which forms an extension of the receptacle bottom and whereby the receptacle is secured in tilted position. 60

I claim:

In a tilting-car, the combination of a roller-mounted tilting receptacle, a toothed gearing to move same, end walls for said receptacles rigidly fixed to the bottom of same, 65 side walls with their lower edges pivoted in an easily disengageable way to the bottom plate of the receptacle, arms to engage the ends of the upper edges of said side walls, and auxiliary end walls fixed on the car 70 frame and connected with said arms, all for the purpose set forth.

In testimony whereof I have hereunto set my hand in the presence of two subscribing witnesses.

AUGUST PREUSSLER.
